(57) **CLAIM**

The ornamental design for a gun safe, as shown and described.

DESCRIPTION

FIG. 1 is a top perspective view of a gun safe, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another top perspective view thereof, the drawer shown in an open position.

The broken lines in the drawings illustrate the portions of the gun safe, which form no part of the claimed design.

1 Claim, 9 Drawing Sheets
